Primary Examiner—Ian Simmons*Assistant Examiner*—Wan Laymon(74) *Attorney, Agent, or Firm*—Finnegan, Henderson, Farabow, Garrett & Dunner LLP**CLAIM**

The ornamental design for a dialysis machine display therefor, as shown and described.

DESCRIPTION

FIG. 1 is an enlarged front elevational view of a dialysis machine display showing my new design;

FIG. 2 is a front perspective view thereof; and,

FIG. 3 is a front view thereof.

The broken lines showing portions of a display for a dialysis machine are included for the purpose of illustrating environmental structure and form no part of the claimed design.

1 Claim, 3 Drawing Sheets**FIG. 1**

FIG. 3
